ABSTRACT: A low-viscosity, low-melting point fluid liquefiable at the pressure and temperature in a pipeline and containing at least 50 percent by volume of carbon dioxide and less than 10 percent by volume of ethane is mixed with crude oil to reduce the viscosity and pour point of the oil while the oil is flowed through the pipeline. The carbon dioxide may later be separated from the crude oil and used in an oil recovery process. Natural gas produced with the oil may be used to form part of the carbon dioxide.

USE OF CARBON DIOXIDE IN A CRUDE OIL PIPELINE

BACKGROUND OF THE INVENTION

This invention pertains to crude oil pipeline operations, and more specifically, to the addition of a low-viscosity, low-melting point liquefied fluid to crude oil in cold areas and transporting the mixture through a pipeline. A major portion of the fluid is made up of carbon dioxide and the fluid contains less than 10 percent by volume of ethane.

Oil, having a wide variation in properties, is produced from many different types of bituminous deposits or subsurface formations which may be remotely located in cold areas like Alaska.

In order to enhance the production of oil, it is frequently desirable to inject a fluid exhibiting some solubility in the oil, for example, carbon dioxide. In some areas, however, there is no economical source of fluid for injection and it would ordinarily be too costly to attempt transport of such fluids to these oil producing areas.

When oil is produced from subsurface formations, the effluent contains oil and gas. The gas is separated from the oil. The separated gas is usually a form of natural gas containing more than fifty percent by volume of hydrocarbons, chief of which is methane. The oil remaining after separation of the gas is commonly referred to as killed crude or stock tank crude. The volume of gas in standard cubic feet per barrel of stock tank crude is commonly referred to as the gas-oil ratio which ratio varies with production history and procedure including reservoir pressure and temperature. Under standard conservation practices, if the gas is rich in hydrocarbons, the gas must be conserved and disposed of in some useful manner. In remote producing areas, there may be no economic use for the natural gas; consequently, there arises a problem of how to dispose of the gas in an economic fashion.

Normally, the killed crude oil is transported in a crude oil pipeline to a refinery or to means for transporting the crude oil to a refinery. In cold areas, the pour point and viscosity of the crude oil may be too high to permit the crude oil to be transported through a pipeline during the cold periods of the year. When the producing area is remote from the refinery and the cold periods are of long duration, it may be impractical to produce crude oil for transportation through a long pipeline.

It has been proposed to transport mixtures of crude oil and lighter hydrocarbons in a pipeline. For examples, reference may be had to U.S. Pat. No. 1,762,423 relating to mixing natural gas with crude oil and U.S. Pat. No. 3,344,583 relating to mixing a hydrocarbon containing at least 10 percent by volume of ethane with crude oil. This invention uses a different fluid and provides a new use of carbon dioxide wherein a fluid rich in carbon dioxide is mixed with crude oil thereby solving one or all of the difficulties just described.

SUMMARY OF THE INVENTION

A low-viscosity, low-melting-point fluid containing at least 50 percent by volume of carbon dioxide and less than 10 percent by volume of ethane is mixed with crude oil and the mixture is transported in a pipeline from one point to another point. At pipeline conditions, the fluid rich in carbon dioxide is a liquid and sufficiently soluble in the crude oil to accomplish a reduction in viscosity and pour point of the crude oil. This method is especially advantageous for crude oil pipelines where cold weather renders the crude practically unflowable. The method also provides a way of conserving natural gas produced with the crude oil and a source of carbon dioxide for use in a producing area requiring carbon dioxide for injection to increase oil recovery. All of these benefits are especially useful in Alaska where oil from North Slope of Alaska could be piped to the oil producing area of Cook Inlet.

The minimum amount of fluid to be added to the crude oil may be stated in several ways. In one method, the minimum amount is sufficient to reduce the viscosity of the crude oil at a temperature of 70° F. by 30 percent or more. In a second

method, the minimum amount of fluid is at least 80 standard cubic feet per barrel of crude oil. In a third, the amount of fluid added reduces the average pour point of the crude oil to a temperature at least 5° F. below the operating ambient temperature of the coldest portion of the pipeline and maintain this pour point during brief shutdown periods.

The fluid is rich in carbon dioxide, that is, it contains at least 50 percent by volume or more of carbon dioxide. Preferably, a fluid will contain more than 75 percent by volume of carbon dioxide. If desired, the carbon dioxide may be separated at a second point and injected into a subsurface formation in a oil recovery process. In addition to being useful in an oil recovery process, carbon dioxide is especially advantageous because of its ability to mix with crude oil at cold temperatures and reduce both the viscosity and pour point of the oil and because it is a normally gaseous nonflammable fluid that has a boiling point especially suited to cold pipeline temperatures. It has the further advantage of either existing naturally in carbon dioxide rich reservoirs, or of being present in amounts of less than 50 percent by volume in natural hydrocarbon gases either produced separately or with the crude oil, or in being readily formed by reacting natural hydrocarbon gases or liquid hydrocarbons with oxygen of air.

DESCRIPTION OF PREFERRED EMBODIMENT

This invention comprises adding at first point to crude oil a fluid containing at least 50 percent by volume of carbon dioxide and containing less than 10 percent by volume of ethane. Carbon dioxide is normally gaseous at one atmosphere of pressure at a temperature of 70° F. and is liquefiable and sufficiently soluble in crude oil at relatively low temperatures and pressures to accomplish the objectives of this invention. Preferably, the fluid will contain at least 75 percent by volume of carbon dioxide.

The minimum amount of carbon dioxide rich fluid added to the crude oil may be stated in terms of standard cubic feet per stock tank barrel of crude oil, or in terms of the amount of fluid required to reduce the viscosity of the crude oil by 30 percent or more, or in terms of the amount of fluid required to reduce the pour point of the crude oil to a temperature of 5° F. below the lowest pipeline temperature. Generally, the amount of fluid added will reduce the pour point to at least -5° F. When the amount of fluid is given in terms of standard cubic feet, standard conditions of pressure and temperature are used which in this case are taking one atmosphere and 60° F. The minimum amount of standard cubic feet added for each stock tank barrel of crude is at least 80 cubic feet. This minimum amount is required to obtain either the necessary reduction in the viscosity or to reduce the pour point as hereinafter described.

The fluid additive rich in carbon dioxide at a temperature of 70° F. and atmospheric pressure (approximately one atmosphere) exhibits a viscosity substantially lower than the viscosity of the crude oil at the same temperature and pressure. In other words, at 70° F. and atmospheric pressure the viscosity in centipoises of the crude oil is at least 10 times the viscosity of the fluid. Since the fluid and carbon dioxide are normally gaseous at 70° F., an even greater difference in viscosity between the crude oil and fluid will exist. For example, the viscosity of carbon dioxide at 70° F. and one atmosphere is about 0.015 centipoise which is less than one-hundredth the viscosity of most crude oils.

The fluid additive is also sufficiently mixable or soluble with the crude oil to accomplish the aims for which the fluid is used. When the fluid rich in carbon dioxide is added to the crude oil to reduce the viscosity, or viscosity and pour point, of the crude oil, the fluid must possess the property of being sufficiently mixable with the crude oil to reduce the viscosity of the crude oil, that is, the mixture of crude oil and fluid will exhibit a lower viscosity than the crude oil by itself. The amount of fluid added should be sufficient to reduce the viscosity of the crude oil at 70° F. by 30 percent or more. For

example, if the viscosity of the crude oil is 50 centipoises at 70° F., the viscosity of the mixture of crude oil and fluid at the same temperature will be 35 centipoises or less. The degree of reduction in viscosity caused by mixing different amounts of a given fluid with the crude oil will vary with the type of crude oil. Generally, the higher the viscosity of the crude oil, the greater will be the effect of a predetermined amount of fluid provided that the oil and fluid properly mix. In all cases, however, where the fluid is added to reduce viscosity or pour point, the amount of fluid added must reduce the viscosity of the crude oil at 70° F. by at least 30 percent. The viscosity at 70° F. of all killed crude oils tested showed a reduction of 30 percent and greater when mixed with 80 standard cubic feet of normally gaseous fluid at a pressure sufficient to form a solution. A procedure for measuring viscosity of mixtures of crude oil and normally gaseous fluids is given by two articles entitled "Physical Properties of Carbonated oils," J. R. Welker and D. D. Dunlop, Volume 228, Aug. 1963, JOURNAL OF PETROLEUM TECHNOLOGY, pp. 873-876, and "Generalized Correlations for predicting Solubility, Swelling and Viscosity Behavior of CO₂-Crude Oil Systems," R. Simon and D. J. Grasse, Volume 234, Jan. 1965, JOURNAL OF PETROLEUM TECHNOLOGY, pp. 102-106. The procedure of Welker and Dunlop maybe readily adapted to colder temperatures.

When the mixture of crude oil and fluid is flowed through a pipeline in a cold environment, for example, operating temperatures below 20° F. and as low as -5° F. and lower, the fluid additive must also have a low melting point or pour point. The melting point should be below -20° F. The melting point for pure carbon dioxide is about -70° F. at 5.2 atmospheres. For reasons hereinafter made more apparent, the fluid exhibits a low enough vapor pressure to be essentially a liquid at cold temperatures and reasonable pipeline pressures, that is, pressures below 500 p.s.i. For example, at 20° F., carbon dioxide is a liquid at 450 p.s.i. At cold conditions, the fluid added to the crude oil should also be sufficiently mixable or soluble with the crude oil and of such a nature as to reduce the pour point of the crude oil. The minimum amount of fluid for cold areas should reduce the pour point of the crude oil to below the ambient or operating temperature around the pipeline at the depth of burial of the pipeline. Generally, the amount added will reduce the pour point of the crude oil to at least 5° below the minimum operating temperature of the pipeline and even greater reductions are desired. Normally, the pour point of crude oil is measured at room pressure in accordance with the procedures set forth in the 1967 revision of Method D97-66 of the American Standards for Testing Materials. Pour point measurement are affected by the thermal stress history of the oil. For this reason, three types of pour points have been measured. These are called the upper point, the lower pour point and the stabilized pour point. Of these, the upper and lower pour points are still included in Method D97-66. Both are significant in the handling of crude oil in cold areas. There are no standardized methods for measuring pour points at elevated pressures. For example, the types of pressures that would be required to hold normally gaseous carbon dioxide in solution with crude oil. The pour points or crude oil-normally gaseous carbon dioxide rich fluid mixtures of this invention were measured at elevated pressures using a 150 milliliter sample bomb containing four, 1/4-inch, nickel balls. Measurements were made using 100 milliliters of crude oil mixed with a preset amount of fluid additive. The bomb was cooled in dry ice at a rate of about 3° F. per minute. Every few minutes the bomb was shaken to determine if the balls could be moved. The temperature at which the balls froze in place is used as the pour point. An average of two or more measurements is used. The number of measurements made depends upon the variation between tests. Procedures for high and low pour point similar to those set forth in ASTM D07-66 were conducted using this bomb. The amount of reduction in pour point caused by mixing a given amount of fluid with crude oil is dependent upon the properties of the fluid and the crude oil. For

a normally gaseous fluid like carbon dioxide, it was found that at least 80 standard cubic feet of fluid per stock tank barrel of crude oil must be added to substantially reduce the pour point of the crude oil. For the colder temperatures higher amounts will be needed. For example, in samples of crude oil having an average pour point of about 0° F., the pour point was a -15° F. when a mixture corresponding to 230 s.c.f. of carbon dioxide per barrel of oil was tested. Carbon dioxide is soluble enough in crude oil at low pipeline temperatures to permit these amounts of carbon dioxide to be mixed with crude oil at reasonable pipeline operating pressures.

When the fluid containing normally gaseous carbon dioxide is added to crude oil to reduce the pour point of the crude oil, it is especially desirable to maintain the pressure of the mixture above the bubble point of the solution during those periods when flow the mixture between pumping or booster stations is interrupted. During these period, if the pressure were permitted to decrease below the bubble point of the mixture, some of the normally gaseous carbon dioxide or other constituents of the fluid would vaporize from the solution. This would decrease the concentration of dissolved fluid in the crude oil and this, in turn, would increase the pour point of the mixture. If the pour point increased to a temperature above the operating temperature of the pipeline, the crude oil would congeal causing a great deal of difficulty. The necessary pressure is usually maintained by pressure applying means and valves; however, there may be instances where these pressure maintenance systems will not function. In such situations, there should be more than enough normally gaseous fluid in the mixture to lower the pour point to the desired level. With an excess of normally gaseous fluid present, partial vaporization of the fluid will maintain the pressure in the pipeline at the bubble point of the solution thereby holding enough carbon dioxide in the crude oil to maintain the pour point to a level below the operating temperature of the pipeline. As a result, the crude oil would not congeal during the shutdown period. When the movement of the mixture in the pipeline is resumed, the oil will still be flowable and the vaporized fluid will redissolve or reliquify. For similar reasons, an excess of normally gaseous fluid should be added when the fluid is used to reduce the viscosity of cold crude oil to render it pumpable.

One advantage in the use of carbon dioxide as a major portion of the fluid is that this material of carbon dioxide may be at least partially generated from natural gas. The natural gas may either be produced separately from gas reservoirs or the natural gas may be obtained by separating the gas from the produced crude oil. The fluid rich in carbon dioxide can be produced by separating natural carbon dioxide from at least a portion of the hydrocarbons in the natural gas or by burning the natural gas to form a combustion gas rich in carbon dioxide either with air or oxygen. If air is used in the burning process, the carbon dioxide may be separated from the combustion gas by conventional processes, such as, the monoethanolamine and hot carbonate process, or some other known separation process. The carbon dioxide rich fluid may then be compressed, liquefied and blended with the crude oil in the pipelines itself. Even if the volume of carbon dioxide is in excess of that soluble in the oil, at cold conditions it is practical to operate with liquid carbon dioxide dispersed in the crude oil.

As mentioned previously, the mixture of fluid and crude oil is flowed through a pipeline to a second point. This second point may be adjacent or near a producing area requiring a source of carbon dioxide for use as an injection fluid in an oil recovery process. In this situation, the use of carbon dioxide as the additive fluid has a still further advantage. The carbon dioxide may be separated from the crude oil-fluid mixture in the pipeline using methods similar to those set out in U.S. Pat. No. 3,344,583. At least part of the separated carbon dioxide may then be injected into a subsurface formation in any oil recovery process wherein a gaseous fluid, especially carbon dioxide, would be useful.

There have been shown, described and pointed out the fundamental novel features of this invention. It will be understood that various omissions, substitutions and changes in the form and details of the described processes may be made or supplied by those skilled in the art of crude oil production and transportation without departing from the spirit of the invention. It is, therefore, our intention to be limited only as required by the scope of the appended claims and reasonable aspects thereof.

We claim:

1. A method of transporting crude oil in a pipeline comprising adding to crude oil at a first point a fluid containing at least 50 percent by volume of carbon dioxide and less than ten percent by volume of ethane to form a mixture of said crude oil and said fluid, said fluid being a liquid at the temperature and pressure in said pipeline, said fluid being further characterized in that said fluid has a viscosity at a temperature of 70° F. substantially less than said crude oil at said temperature and will mix with said crude oil to reduce the viscosity of said crude oil and the amount of said fluid being sufficient to form a mixture having a viscosity at said temperature at least 30 percent less than the viscosity of said crude oil at said temperature, and flowing said mixture through said pipeline to a second point.

2. The method of claim 1 wherein natural gas is used to form at least part of the carbon dioxide portion of said fluid added to said crude oil.

3. The method of claim 1 wherein at least a part of the carbon dioxide portion of said fluid is separated from the mixture at the second point and is injected into a subsurface formation in an oil recovery process.

4. The method of claim 3 wherein natural gas is used to form at least part of the carbon dioxide portion of said fluid added to said crude oil.

5. The method of claim 1 wherein the fluid added to the crude oil contains at least 75 percent by volume of carbon dioxide.

6. The method of claim 5 wherein natural gas is used to form at least part of the carbon dioxide portion of said fluid added to said crude oil.

7. The method of claim 5 wherein at least a part of the carbon dioxide portion of said fluid is separated from the mixture

at the second point and is injected into a subsurface formation in an oil recovery process.

8. The method of claim 7 wherein natural gas is used to form at least part of the carbon dioxide portion of said fluid added to said crude oil.

9. A method of transporting crude oil in a pipeline comprising adding to crude oil at a first point fluid containing at least 50 percent by volume of carbon dioxide and less than 10 percent by volume of ethane to form a mixture of said crude oil and said fluid, said fluid being a liquid at the temperature and pressure in said pipeline, said fluid being further characterized in that said fluid has a viscosity at a temperature of 70° F. substantially less than said crude oil at said temperature and will mix with said crude oil to reduce the viscosity of said crude oil and the amount of said fluid being at least 80 standard cubic feet per barrel of said crude oil in said mixture; and flowing said mixture through said pipeline to a second point.

10. The method of claim 9 wherein natural gas is used to form at least part of the carbon dioxide portion of said fluid added to said crude oil.

11. The method of claim 9 wherein at least a part of the carbon dioxide portion of said fluid is separated from the mixture at the second point and is injected into a subsurface formation in an oil recovery process.

12. The method of claim 11 wherein natural gas is used to form at least part of the carbon dioxide portion of said fluid added to said crude oil.

13. The method of claim 9 wherein the fluid added to the crude oil contains at least 75 percent by volume of carbon dioxide.

14. The method of claim 13 wherein natural gas is used to form at least part of the carbon dioxide portion of said fluid added to said crude oil.

15. The method of claim 13 wherein at least part of the carbon dioxide portion of said fluid is separated from the mixture at the second point and is injected into a subsurface formation in an oil recovery process.

16. The method of claim 15 wherein natural gas is used to form at least part of the carbon dioxide portion of said fluid added to said crude oil.
